UNITED STATES PATENT OFFICE.

EDWIN LAWRENCE COPSEY, OF OLD HEATH, COLCHESTER, ENGLAND, ASSIGNOR TO
F. W. BRACKETT & COMPANY LIMITED, OF COLCHESTER, ENGLAND.

VALVELESS ROTARY PUMP.

1,223,036.

Specification of Letters Patent. Patented Apr. 17, 1917.

Application filed April 4, 1916. Serial No. 88,842.

To all whom it may concern:

Be it known that I, EDWIN LAWRENCE COPSEY, a subject of His Majesty the King of Great Britain and Ireland, residing at 5 Old Heath, Colchester, in the county of Essex, England, have invented a new and useful Improvement in Valveless Rotary Pumps, of which the following is a specification.

- 10 The present invention relates to improvements in valveless rotary pumps of the class in which the piston not only rotates around an eccentrically arranged pin secured to the casing but reciprocates within a cylindrical 15 hole in the driven element at right angles to the axis of rotation, the driven element thus formed constituting a cylinder, revolving in a casing furnished with suction and delivery ports.
- 20 The main objects of the invention are to provide the pump with means for enabling the cylinder of same to be driven by a high speed motor, and with an improved bearing for the piston, which bearing also enables 25 that part of the cylinder which is subject to wear to be self adjusting with respect to the casing. Other objects of the invention will be referred to in the following description.

The present invention consists of a rotary 30 pump in which the driving means consists of a shaft having driving means co-acting with means at or about the periphery of the piston containing driven cylinder. The piston operating in said cylinder is furnished 35 with a slot midway between its ends in which an eccentrically disposed non-rotating pin, having a rigid support at each end, is disposed to slide.

According to one form of the invention 40 the driving shaft is provided with a toothed element or elements adapted to co-act with and drive a toothed element or elements on the cylinder such toothed elements being preferably located inside the pump casing. 45 This arrangement frees the casing and cylinder portion of the usual central driving shaft and enables a longer and rigid non-rotating bearing pin to be provided for the piston which reciprocates in the cylinder: 50 and also enables the cylinder to move relatively to the casing so that a close contact

or seal may be obtained therewith at the necessary points without a very exact fit.

In the accompanying drawing which illustrates one example of construction:— 55

Figure 1 is a longitudinal section on line 1—1 of Fig. 2, and

Fig. 2 is a cross section on line 2—2 of Fig. 1.

As shown, the piston 1 reciprocates in an open-ended cylinder 2, the latter revolving in a casing 3 furnished with a suction port 4 and a delivery port 5.

The piston 1, the opposite ends of which are rounded to conform to the wall of the casing 3 is slotted midway between its ends to receive two plates 6, between which works a roller 7 mounted on a pin 8 rigidly secured in the end walls of the casing 3.

The pin 8 is eccentrically disposed with respect to the axis of rotation of the cylinder to a degree equal to a half of the travel of the piston.

The cylinder 2 is provided on one side with a ring of teeth 9 adapted to engage 75 with teeth provided on a pinion 10 keyed on a shaft 11 arranged parallel with the pin 8 and with the axis of rotation of the cylinder 2. The shaft 11 is mounted in bearings 12 and 13 one on each side of the pinion 10, the bearing 13 being made water tight by means of a stuffing box and gland 14. The outer end of the shaft 11 is provided with means to enable same to be coupled to an electric motor. 80

As shown in Fig. 1, the end 15 of the casing is made removable, though if desired both ends may be so formed, further if desired a second ring of teeth may be provided on the other side of the piston adapted to 90 engage with a second pinion provided on the shaft 11.

By the arrangement illustrated it is possible to provide the driving shaft with a long bearing on each side of the pinion and 95 also a long bearing on the pin 8 for the piston 1.

For the purpose of providing the seal between the sides of the cylinder and the sides or ends of the casing and at the same time 100 to prevent metallic contact between said parts, a slight clearance is provided, which

clearance, when in use, becomes filled with whatever medium is being pumped. Frictional losses and wear are thereby overcome, the film of liquid serving as a buffer between the surfaces.

5 By reason of the fact that the piston has a free movement on the eccentrically disposed roller, the cylinder is able to automatically adjust itself for any wear that 10 takes place at the periphery thereof as the pressure of the fluid in the discharge port always tends to press the cylinder up to the suction port.

15 The action of the pump is as follows:—

15 Assuming the cylinder 2 to be rotated in the direction of the arrow, Fig. 2, the end 1^a of piston 1 will be brought into communication with the suction port 4, the receding piston drawing after it a quantity of fluid 20 equal to the travel of the piston multiplied by the area of the piston. As the piston reaches the end of its stroke communication with the suction port is cut off by the edge 2^a of the cylinder 2. The end 1^a of piston 25 1 has now come into a position similar to that occupied by the end 1^b (Fig. 2) and the rotary motion being continued the contents are expelled by the now oncoming piston into the discharge port 5, the cycle of events, 30 as far as the end 1^a is concerned, being complete when the piston occupies the position shown in Fig. 2, the edge 2^a cutting off communication with the discharge port 5. The same cycle of events takes place with respect to the end 1^b. It will therefore be seen 35 that the pump is continuously sucking and discharging without changing the direction of the fluid during its passage through the pump.

What I claim is:—

1. In a valveless rotary pump, the combination of a casing, an eccentrically disposed non-rotating pin rigidly supported at both ends in said casing, a cylinder located in said casing and adapted to rotate around 45 said pin, a driving shaft, a toothed element on said shaft, a long bearing for said shaft located on both sides of said toothed element, a toothed element formed on the periphery of the driven cylinder adapted to co-act with 50 the toothed element on the driving shaft, a piston reciprocating in and rotating with said cylinder, and a slot provided in said piston midway between its ends in which said non-rotating pin is adapted to slide 55 during the rotative movement of the piston.

2. In a valveless rotary pump, the combination of a casing, an eccentrically disposed non-rotating pin rigidly supported at both ends in said casing, a roller mounted on said 60 pin, a cylinder located in said casing and adapted to rotate around said roller, a driving shaft, a toothed element on said shaft, a long bearing for said shaft located on both sides of said toothed element, a toothed element formed on the periphery of the driven cylinder adapted to co-act with the toothed element on the driving shaft, a piston reciprocating in and rotating with said cylinder, a slot provided in said piston midway 65 between its ends and plates secured within said slot between which said roller is adapted to slide during the rotative movement of the piston.

In witness whereof I have hereunto set 70 my hand.

EDWIN LAWRENCE COPSEY.
